UNITED STATES PATENT OFFICE.

ELIAS H. KELLEY, OF NEW YORK, N. Y.

COIN CONVEYING AND RECEIVING MECHANISM FOR VENDING-MACHINES.

1,204,454.

Specification of Letters Patent. Patented Nov. 14, 1916.

Original application filed December 17, 1909, Serial No. 533,638. Divided and this application filed October 27, 1910. Serial No. 589,303.

To all whom it may concern:

Be it known that I, ELIAS H. KELLEY, a citizen of the United States, residing in the borough of Manhattan, city, county, and 5 State of New York, have invented a new and useful Improvement in Coin Conveying and Receiving Mechanism for Vending-Machines, of which the following is a description.

10 This invention has reference to vending machines and especially to the coin-controlled type of such machines; but, particularly, my invention relates to conveyers and receptacles for the coin deposited in the machine.

15 The mechanism of this invention is intended for use in machines of the type claimed in my application, Serial No. 533,638, filed Dec. 17, 1909, of which latter 20 this application is a division.

Among the objects of my invention may be noted the following: to provide a receptacle, for the coins deposited in the machine, so located as to catch all the coins deposited in the machine regardless of which slide said coin is primarily deposited in; to provide a receptacle having separate compartments for the coins of different denomination and so located in relation to the chain 25 conveyer as to receive, in a particular compartment, only the coin intended; to provide means in connection with a receptacle for coins which will prevent the receptacle from being withdrawn from the machine with the lid open or with the lid unlocked; to provide means in connection with a receptacle for coins which will prevent the receptacle from being placed in the machine with the lid closed; to provide means whereby a coin 30 receptacle can be placed in the machine only in open condition and which will be held in the machine in that condition, in combination with means whereby the lid will be automatically closed and locked when the 35 said receptacle is withdrawn from the machine; to provide means whereby a coin-box, for a vending machine, can be identified as belonging to a given machine or type of machines, thus rendering identification 40 easy, continual defrauding impossible, and facilitating the establishment of book-keeping and checking systems; to provide means by which a coin-box can be used only in a given machine according to predetermina-

tion, and in no other; to provide means by 55 which the coins are conveyed to and properly deposited in the receptacle or coin-box; and to provide a combination of means by which the foregoing objects are secured cheaply, effectively and positively. 60

With the above objects in view and others which will be detailed during the course of this description, my invention consists in the elements, mechanisms, parts and features, and combinations of elements and 65 mechanisms all as hereinafter described and claimed.

In order that my invention may be clearly understood, I have provided drawings 70 wherein:

Figure 1 is a vertical sectional view of so much of my aforesaid vending machine as is deemed necessary to illustrate my invention of this application; Fig. 2 is a vertical sectional view at a right-angle to that of 75 Fig. 1 and on the line 2—2 of the latter; Fig. 3 is an end elevation of the receptacle and surrounding portion of the machine, the front of the frame being in section; Fig. 4 is an enlarged sectional detail of the receptacle and means for holding the lid open 80 and locking the lid when closed; and Fig. 5 is a broken plan and partial section of the coin-box or receptacle.

Referring to the drawings, the numeral 1 85 indicates the base of the frame, 2 the opposite side-plates, and 3 the back-plate, these parts being fitted and bolted together in any suitable manner to provide a rigid and strong supporting-frame, the top-plate and 90 front-plate of the machine not being shown since the figures have been curtailed to restrict the same to an illustration of my present invention. Viewing Figs. 1 and 2, it will be seen that the lower portion of the 95 frame extends forward of the driving-shaft to provide a support 6 for the slide-plate 7, which may carry any number of coin-slides 8 according to the use or purpose of the machine. In front of the support 6, the 100 frame at its base, has an opening which is closed by a door 9, hinged at its bottom, as at 10, to the base of the frame, which may be provided with a spring-lock, as will be obvious. This door forms the closure for 105 a space below the support 6 in which a coin-box 11, is supported, together with co-operating mechanism which will be described, said

box being partitioned to provide chambers 12, 13 and 14, of varying size, for the reception of coins of different value. The coin-box 11 is provided on its opposite sides with runners 15 which travel upon the guide-rails 16, extending across the base of the frame of the machine, the said coin-box being thus capable of being easily slid into the machine and maintained in proper position between the two said rails. The frame-portion 17 of the machine, at its lower edge adjacent the top of the door 9 and at opposite ends of the coin-box, is provided with dogs 18, pivoted at 19, each of said dogs being under control of a spring 20, fixed to the said frame and engaging the portion 18 of said dog, the latter having its depending portion 21 in position such as to coöperate with the complementary inclined lugs 22 secured to the opposite ends of the lid 23 of the coin-box adjacent its free or upper edge. The dogs and lugs coöperate to close the lid 23 of the coin-box, since the lower portion 21 of said dogs is directly in the path of said lugs when the coin-box is being removed; that is to say, as the box is withdrawn from the machine, the spring 24, supported as presently described, will exercise its normal tendency to close said lid, thus presenting the lugs 22 in the path of said dog-portion 21. Since, however, said dog, in this direction of movement of the box, will yield against the pressure of the spring 20 said dog will only have a tendency to press closed the lid 23 and snap the spring-lock 25 thereof; but, to insure that the lid be tightly closed as the box is withdrawn from the machine, said lugs 22 will engage the lower edge 26 of said frame which, being rigid, will snap the spring-lock 25 and lock the lid, thus enabling the free withdrawal of the box from the machine. The lugs 22 also prevent the placing of the coin-box in the machine with the lid closed, since the lower ends of the depending portions 21 are slightly below the lower edge 26 of the frame and the dogs will engage the said lugs when the lid is closed and cannot yield, owing to the portion 18 being in contact with the frame-portion 17. Therefore, it becomes necessary to first open the lid and lay it back against its spring pressure upon the top of the box, thus allowing said box to be placed in the machine without interference with the dog. As soon as the box is well in the machine, the lid will be released and its spring will force it into engagement with the guard 27, which latter will hold said lid wide open so that the coins can freely pass through the openings 28 in the box, and into their proper compartment 12, 13 or 14. The top 29 of the coin-box is hinged to the front wall thereof along the upper edge of the latter, as indicated at 30, and at its opposite side said top is provided with a spring-lock, see Fig. 1, indicated by 31, this construction

enabling the entire top of the box to be thrown wide open for the removal of the contents thereof.

Viewing Figs. 1, 2 and 3, when the main-shaft 32 is rotated by either motor or crank, 70 the sprocket-wheel 33 carried thereby will be rotated since it is fixed to the shaft, such rotation driving the sprocket-chain 34 which rotates the sprocket-wheel 35 carried by the short-shaft 36 journaled in the standard 37 and a bracket 38 carried by the adjacent standard 37. Shaft 36 carries a pinion 39 meshing with a gear 40 carried by a shaft 41, journaled above the shaft 36, in the standard 37. Shaft 41 carries a pair of 80 sprocket-wheels 42 each of which drives a chain 43 to which the coin-cups 44 are connected. In rear of the standard 37 is another pair of bearings, not shown, which support a pair of sprocket-wheels 46, similar 85 to those in the front bearings around which the respective cup-chains also run, the said chains being thus compelled to take a course in the direction of the arrow, Fig. 1, which will maintain the said cups in a horizontal 90 position with several of them in horizontal alignment so as to catch the coins which pass from the chutes, 47, 48 and 49, suitably secured to the bottom of the slide-plate 7. Viewing Fig. 1, every other link 50 of the chain 43 has a cup 44 fixed thereto so as to travel with the chain in a fixed position relatively to said link, the links, extending between each pair of cups, spacing the latter so that a uniform distance will always be maintained between the cups, and the latter can travel the circuit prescribed by the two sets of sprocket-wheels without interference. As shown in Fig. 2, the chute 47 extends toward the right-hand side of the machine 95 and empties into the coin-cups 44, which are arranged in single form and are in position to receive the five-cent piece from the nickel-slide, which is on the left side of the machine. The chute 48 is under the dime-slide and is also directed toward the right side of the machine and deposits its coin in the left or small side of the double cups 44, while the chute 49 is under the quarter-slide, is directed toward the chute 48 and deposits its coin in the right-hand side of the double cups 44, the latter being made double and arranged as shown to economize space, cheapen and simplify the machine. The cups, as the chains 43 move along in the 100 direction of the arrow in Fig. 1 are given a complete turn so as to dump the coins into the box 11, through the opening 28 in the top thereof, which extends across the same from side to side. The spring 24 coiled about the hinge-pin 51 of the lid normally tends to close said lid, one end of the spring being secured to the lid at 52 and the other end to the box at 53. Opposite the guard 27, a back-plate 54 is fixed to the beam 55, said 105 110 115 120 125 130

plate and guard having the function of accurately directing the coins into the box 11, through the openings 28, and preventing said coins from being dumped in or deflected 5 to any other portion of the machine. The guard 27 also has the function of retaining the door 23 open while the box is in the machine.

The chains, sprockets and cups constitute 10 a coin-conveyer and the amount of travel imparted thereto is approximately the distance of one coin-cup for every rotation of the driving-shaft 32. Hence, for every operation of the machine the conveyer will 15 carry the contents of a given cup under and into the light of a lamp 56 so that it may be inspected through the transparency 57, and a person tampering with the machine or trying to defraud the same by slugs or 20 checks, etc., can be instantly detected. This particular feature forms no part of my present invention.

Referring to Figs. 2 and 3, means are provided for identifying a machine or the 25 location thereof, and for preventing a box intended for a given machine, from being used with any other machine. This means, in the instance shown, consists of a dove-tailed lug 58 fixed to the bottom of the 30 box 11, and coöperating with a guide 59 having a groove complementary in form to said lug, said guide being carried by the base-plate 1. Obviously, the position, size and shape of this "key" to a given machine 35 and its coin-box can be varied indefinitely. Thus an infallible means for the purposes stated is and can be provided and the same forms an important feature of my invention since it makes the coin-boxes non-inter- 40 changeable; that is to say, said boxes are provided with means heretofore described whereby a given box can be used only in one machine constructed and adapted specially for the reception of said box. This 45 means or "key" may be provided in any number desired in each machine and may, obviously, be located in an indefinite number of positions, whereby the owners or users of a given line of machine may be assured of 50 the return of the coin-box to the proper machine from which it has been removed. This feature of my invention also enables a user or owner of a given number of machines to locate and identify, at a given point, in a 55 large city, for example, any machine in the coin-box of which a coin other than a good coin may have been deposited, and also enables the auditor to credit each machine with its earnings. This "key" also enables 60 a system of book-keeping to be established with reference to any one or any group of machines. Ordinarily, each machine will have at least two boxes, one to be inserted when the other is taken away. As shown in 65 Fig. 2, the coin-boxes are provided with

three compartments, one for each denomination of coins, for example, five, ten and twenty-five cents, thus avoiding the necessity of sorting the coins upon removal of the box. Obviously, the coin-boxes will be 70 partitioned and made of a size corresponding with the use or character of the machine and may, in some instances, be provided with only one compartment and in others with more than three. As has been 75 pointed out, the coin-boxes are so constructed that the lid will be shut tight and locked as the box is withdrawn from the machine, thus preventing employees from gaining access to the contents when the boxes 80 are collected in regular course of business. Also, to insure that the coins will be deposited from the conveyer into the boxes, means have been provided, as described, which prevent the box being inserted in the machine 85 in other than an open condition, this open condition being maintained, as shown in Figs. 1 and 4, the spring surrounding the hinge of the lid, however, normally tending to close the latter. Hence, the importance of 90 my invention in this particular resides in the fact that the lid is automatically closed and locked as the box is removed from the machine and that the box cannot be placed 95 in the machine without having the lid wide open for reception of the coins by the box.

Other parts and mechanisms of my machine, forming the subject-matter of my aforesaid application, which have been incidentally shown in the drawings form no 100 part of my present invention and have not been specifically described.

While I have described my coin receiving mechanism including the chutes, conveyers and coin-box in connection with a coin-controlled apparatus of the particular type shown in my aforesaid parent application, I desire it distinctly understood that my invention is not limited for application to 105 the particular machine, but that I purpose 110 that the same shall be used in any relation possible and, in consequence, my claims will not be limited to any particular machine but shall be comprehensive of the mechanism irrespective of the machine in which it 115 may be used or found.

Having thus described my invention what I claim and desire to secure by Letters Patent is:

1. In combination, a plurality of conveyers for vending machines; a coin-receiving box having a plurality of compartments and an opening into each compartment; the said conveyers being arranged, respectively, in co-operative relation to the compartments of 120 the box; and means for operating the conveyers whereby the coins carried by the conveyers will be dropped into the respective compartment of the box.

2. In combination in a vending machine, 125

- a coin-box provided with a lid; means for normally holding said lid open when the box is in the machine; said lid and means also aiding in directing the coins into the box; 5 a conveyer for depositing the coin in the box; and means between the box and the conveyer coöperating with the lid and first-named means for directing the coins in the box.
- 10 3. In combination in a vending machine, a plurality of coin-chutes; a plurality of conveyers coöperating with said chutes, one

of which is double and coöperates with two of said chutes; and a coin-box located under the conveyers and having an opening therein for receiving the coins from the conveyers. 15

In testimony whereof I have hereunto signed my name in the presence of two subscribing witnesses.

ELIAS H. KELLEY.

Witnesses:

E. A. NASH,
M. HERSKOVITZ.
